Patented Aug. 16, 1921.

2 SHEETS—SHEET 2.

UNITED STATES PATENT OFFICE.

JAY E. CROSS, OF TAKOMA PARK, MARYLAND.

APPARATUS FOR CLEANING BOOK-COVERS AND THE LIKE.

1,387,884.

Specification of Letters Patent. Patented Aug. 16, 1921.

Application filed May 27, 1920. Serial No. 384,707.

To all whom it may concern:

Be it known that I, JAY E. CROSS, a citizen of the United States, residing at Takoma Park, in the county of Montgomery and 5 State of Maryland, have invented a certain new and useful Improvement in Apparatus for Cleaning Book-Covers and the like, of which the following is a full, clear, and exact description.

- 10 In the manufacture of book covers and the like, upon which titles and other markings are done in gold, silver and other metal leaf or foil, it is essential to the economical and proper accomplishment of such marking that 15 all surplus metal leaf be removed from the articles and recovered for future use.

Numerous devices and machines have been produced for performing this process of cleaning off and recovering the metal leaf or foil, but, owing to various imperfections in design and operation, they have failed commercially to supplant hand-work to any appreciable extent.

- 20 The object of this invention is to provide 25 a machine which will as nearly as possible simulate the old hand method of cleaning book covers and the like, whereby the work may be greatly expedited without in any way sacrificing the quality of the work 30 performed to the increased speed of production of the finished article, and moreover, in addition to my machine performing the work as well, if not better, than it can be done by hand, it eliminates the loss of the 35 particles of gold leaf, which loss, during the cleaning by hand, is almost impossible to avoid, and also prevents particles of other metal foil or material used from being scattered or carried about in the air as a menace 40 to health.

The invention consists in a machine for 45 cleaning book covers and the like, comprising a substantially normally closed chamber in which are mounted means for feeding the book covers or the like through the machine and devices for rubbing or brushing the covers as they are fed, the chamber being connected with apparatus for creating a suction therein whereby all surplus metal leaf 50 is removed from the chamber and conveyed to and deposited in a proper receptacle, all as I will proceed now to explain and finally claim.

In the accompanying drawings illustrat-

ing the invention, in the several figures of 55 which like parts are similarly designated, Figure 1 is a side view of the machine. Fig. 2 is an end view thereof. Fig. 3 is a partial sectional plan view, on a larger scale, of the feeding and cleaning devices and their 60 operating mechanism, the top plate of the chamber being removed. Fig. 4 is a partial sectional side view, on a still larger scale, of the parts shown in Fig. 3. Fig. 5 is a section taken in the plane of line 5—5 of Fig. 65 4. Fig. 6 is a section somewhat similar to that shown in Fig. 5 and illustrating a modified form of cleaning device.

The machine comprises a stand 1 upon which are mounted the frame 2 and a motor 70 3 and power shaft 4 driven by the motor.

Upon the frame 2 is supported the casing or working chamber 5 having a top 6 and bed 6' provided with recesses 7 in which are mounted resilient feed rollers 8 of rubber 75 or the like frictional resilient material. The shafts 9 of these rollers extend from side to side of the chamber and are journaled in these sides, as shown at 10, Fig. 3. All of the shafts 9 extend outside of the chamber at 80 one side and are provided with bevel-pinions 11 which mesh with complementary bevel-gears 12 mounted on a shaft 13 supported in suitable bearings 14 carried by the chamber 5. One end of shaft 13 carries a gear 15 85 which is driven by a gear 16 on shaft 17, which shaft is in turn driven from the power shaft 4 by means of a belt 18 and stepped pulleys 19 and 20. By this arrangement it will be seen that the speed of the feed rollers 90 8 and the resulting rapidity of feed of the book covers or other articles through the machine may be varied to suit the operating conditions, as desired.

Mounted within the chamber 5 is a frame 95 21 which carries a plurality of contact rollers 22 having their axes in vertical alignment with the axes of the feed rollers 8 and this frame is provided with tensioning devices comprising bolts 23 which pass through 100 the bottom 24 of the chamber 5 and are fitted with springs 25 and adjusting nuts 26 whereby any desired pressure of the rollers 22 upon the rollers 8 may be obtained within certain limits.

Between the rollers 8 and 22 and extending the full length of the chamber 5 is a flat strip 27 adapted to support the thin

flexible connecting back member of a book cover. A number of these strips made in various thicknesses and widths may be provided to accommodate book covers of various thickness and back members of various width, all of the strips being interchangeable in the machine.

Another frame 28 similar to the frame 21 is also mounted in the chamber 5 above the 10 frame 21, this frame 28 being supported for vertical adjustment by means of screws 29, (see Figs. 4 and 5), and this frame carries a plurality of parallel rods or guides 30 which support, by means of bearing lugs 31, the 15 holders 32 for the cleaning devices. By means of the screws 29 the pressure of the cleaning devices upon the book covers or other articles to be cleaned may be varied as desired.

20 Each holder 32 has a pivot joint 33 at its end in which is pivoted one end of a connecting link 34 working in an adjustable slotted plate 34' and having its other end pivoted to an eccentric strap 35 which encircles an eccentric 36 and is held in alignment thereon by a set-screw 37 working in a peripheral slot 38 in the eccentric. The plates 34' are made adjustable so as to accommodate the adjustment of the frame 28 by the 25 screws 29.

30 All of these eccentrics 36 are mounted on a shaft 39 but at various angles with relation to each other, and this shaft 39 is driven from the power shaft 4 through a belt 40 and 35 pulleys 41 and 42, described more in detail hereinafter. By this arrangement it will be seen that the holders 32 and with them the cleaning devices, presently described, are given a reciprocatory movement transversely 40 of the machine.

45 In practice I have found that there are two sorts of cleaning devices especially adapted for this work. One is a brush 43 (see Fig. 4) made of fiber or wire according to the material operated upon, and the other is a rubbing device 44 (see Fig. 6) made of blocks 45 of rubber or other mild abrasive substance, and in order to make the machine capable of use with either, I have developed 50 the holders 32 above mentioned.

55 Each holder 32 comprises a pair of channel members 46 spaced apart and connected at one end as shown at 47, its other end being provided with slots 48 in which is seated a plate 49 provided with a pair of adjusting or clamping screws 50 having lock nuts 50' (see Fig. 6).

60 The brushes 43 or rubbing devices 44 are made with grooved sides 51 of such contour as to form a snug sliding fit with the channel members 46 of the holders.

65 It will be noted, by reference to Fig. 4, that the side of the chamber opposite to the eccentrics is provided with a plurality of openings 52, one in line with each holder 32.

These openings are provided for the purpose of inserting, removing, or replacing the brushes 43 or rubbing devices 44 as follows:— The frame 28 is raised by operating the screws 29 until the tops of the holders 32 are 70 in line with the tops of the openings 52, then the plates 49 are removed and the brushes or rubbing devices, whichever are to be used, are inserted in the holders their grooved sides registering snugly with the channel 75 members of the holders. Then the plates 49 are replaced and the screws 50 run in until they firmly clamp the brushes or rubbing devices against the ends 47 of the holders, the lock nuts 48 being then tightened down 80 against the plates 49 to maintain this adjustment.

I have found that in operating the machine with the rubbing devices 44 instead of the brushes, it is well not to have them 85 move over the work quite as rapidly as the brushes are operated, and for making this change in speed of reciprocation of the holders 32, I make the pulleys 41 and 42 with steps for one shift so that when the belt is 90 changed from one step to the other a corresponding change in speed of reciprocation of the holders will be accomplished.

As hereinbefore stated, the chamber 5 is 95 practically normally a closed chamber and to the bottom of this chamber I connect the suction pipe 53 of a fan 54 driven by a belt and pulley arrangement 54' or the like from shaft 4. The outlet 55 of this fan leads to a settling box 56 connected by a chute 57 100 with a collection receptacle 58. By this arrangement all of the metal leaf or foil which is removed from the articles operated on will be exhausted from the chamber 5 and finally deposited in the receptacle 58 from 105 which it may be emptied from time to time as required.

110 In operation, the book covers or the like are placed upon the table 59 with the side which is to be operated upon up and the connecting member of the back-portion of the cover lying over the strip 27. This makes the whole surface to be operated upon lie in substantially one and the same plane. The cover is then moved into the chamber until it is caught and fed by the feed rollers 8 and from then to the end of the cleaning 115 operation when the cover emerges clean from the opposite end of the machine the operation is automatic, the brushes or rubbing devices traveling transversely back and forth across the exposed surface of the cover removing all superfluous foil or leaf and this latter being caught up by the suction fan and deposited in the collection receptacle. 120

125 It is to be understood that I do not consider my invention as limited to the specific embodiment herein shown and described, as it is obvious that various changes may be made in details of construction and arrangement 130

ment of parts without departing from the spirit of the invention or the scope of the following claims.

What I claim is:—

- 5 1. In an apparatus for cleaning book covers and the like, a feed mechanism comprising a plurality of resilient feed rollers and pressure rollers coöperating therewith for conveying the book covers through the machine, and a plurality of cleaning devices having a reciprocatory motion in a direction transverse to the direction of feed of said covers for cleaning said covers during their passage through the apparatus.
- 10 2. In a machine for cleaning book covers and the like, a plurality of power-driven feed rollers for conveying the covers through the machine, a plurality of pressure rollers coöperating with said feed rollers, and a plurality of cleaning devices adjustably supported above said covers and having a reciprocatory motion thereover in a direction transverse to the direction of feed thereof.
- 15 3. In a machine for cleaning book covers and the like, a casing, a stationary bed mounted therein and upon which said covers are supported, a plurality of feed rollers in said bed for propelling the covers through the machine, a frame mounted in said casing and carrying a plurality of pressure rollers coöperating with said feed rollers, said frame being normally spring-pressed toward said bed, a second frame 30 mounted in the casing and adjustably supporting a plurality of cleaning devices, means for imparting rotary motion to said feed rollers, and means for imparting reciprocatory motion to said cleaning devices.
- 35 4. In a machine for cleaning book covers and the like, a casing forming a substantially closed chamber, means for treating
- 40 the covers through said chamber; cleaning devices located in said chamber and having a reciprocatory motion in a direction transverse to the direction of feed of the covers, whereby any surplus metal foil or the like is removed from the covers, and foil recovering means including suction apparatus communicating with said chamber and adapted to remove therefrom all foil cleaned from said covers.
- 45 5. In a machine for cleaning book covers and the like, a bed, a plurality of feed rollers located therein, a frame, a plurality of pressure rollers mounted therein and coöperating with said feed rollers to feed book covers through the machine, resilient connections between said frame and bed for normally drawing the frame toward the bed, a second frame carrying a plurality of cleaning devices in such manner as to permit transverse reciprocation thereof, means for adjusting said last-mentioned frame toward and away from said bed, means for 55 imparting rotary motion to said feed rollers, and means for imparting reciprocatory motion to said cleaning devices.
- 60 6. In a device for cleaning book covers and the like, a bed on which said covers are supported during the cleaning operation, and a strip running the length of said bed and having its upper face in a plane above the plane of said bed, whereby as said covers are supported on said bed their flexible back portions will be supported by said strip in the same plane as the upper faces of their side portions.
- 65 7. In testimony whereof I have hereunto set my hand this 26th day of May, A. D. 1920.
- 70 8. JAY E. CROSS.

Witnesses:

W. H. FINCKEL, Jr.,
LILLIE M. KEELER.

It is hereby certified that in Letters Patent No. 1,387,884, granted August 16, 1921, upon the application of Jay E. Cross, of Takoma Park, Maryland, for an improvement in "Apparatus for Cleaning Book-Covers and the like," errors appear in the printed specification requiring correction as follows: Page 3, line 42, claim 4, for the word "treating" read *feeding*, and line 43, after the word "chamber" strike out the semicolon and insert a comma; and that the said Letters Patent should be read with these corrections therein that the same may conform to the record of the case in the Patent Office.

Signed and sealed this 6th day of September, A. D., 1921.

[SEAL.]

KARL FENNING,
Acting Commissioner of Patents.
